UNITED STATES PATENT OFFICE.

THEODORE A. MILUTIN, OF DEARBORN, MICHIGAN.

ANTIFREEZING DEVICE FOR RADIATORS.

Application filed November 24, 1920. Serial No. 426,205.

To all whom it may concern:

Be it known that I, THEODORE A. MILUTIN, citizen of the United States, residing at Dearborn, county of Wayne, State of Michigan, have invented a certain new and useful Improvement in Antifreezing Devices for Radiators, and declare the following to be a full, clear, and exact description of the same, such as will enable others skilled in the art to which it pertains to make and use the same, reference being had to the accompanying drawings, which form a part of this specification.

My invention relates to a device designed to insure the water circulating through the cooling system of an internal combustion engine against freezing during cold weather when the engine is not in operation.

The object of the invention is to provide means whereby the water may be drained from the cooling system and delivered to an anti-freezing container designed to maintain the water at a sufficiently high temperature that it may not freeze and to return the warm water to the circulating system of the engine that its heat may aid the ignition of the gas delivered to the combustion chamber of the latter.

In putting this invention into effect a pump is employed adapted to drain the water from the water cooling circulating system of the engine upon parking the motor vehicle for any considerable period or upon housing the car over night, the water being delivered thereby into a heat retaining container of the so called "thermos" type, from which the warm water is afterwards withdrawn and returned to the water circulating system of the engine when it is again desired to drive the vehicle;—the pump being operated either manually or through power derived from the usual "starter" employed to "crank" the engine.

A further object of the invention is to provide means whereby the operation of the pump and the delivery of water to and from the water circulating system may be controlled from the driver's seat.

With the foregoing and other objects in view which will appear as the description proceeds, the invention further resides in the combination and arrangement of parts and in the details of construction hereinafter described and claimed, it being understood that changes may be made in the precise em-

bodiment of the invention herein disclosed without departing from the spirit of the same.

In the drawings accompanying this specification:

Figure 1 is a vertical longitudinal sectional view through a fragmentary portion of a motor driven vehicle showing the invention connected with the water circulating system of a prime mover.

Figure 2 is a view partly in section and partly in elevation showing the pump, and pipes leading therefrom to a plural valve casing, in turn connected with the radiator of an internal combustion engine, as installed upon motor vehicles,—the valves housed in the casing being adapted to control the passage of water to and from the radiator and to and from a heat retaining water container,—the view shows the position occupied by the valves when the water is passing from the heat retaining water container back to the radiator.

Figure 3 is a sectional view through the plural valve chamber showing the valves housed therein in the position they occupy when water is being withdrawn from the radiator and the water jacket of the engine, for the delivery to the heat retaining water container.

Figure 4 is a side elevation of the plural valve chamber, showing means for simultaneously operating the several valves.

Figure 5 is a horizontal cross-sectional view through the plural valve chamber.

Figure 6 is a cross-sectional view through the valve chamber taken on or about line 6—6 of Figure 4.

Figure 7 is a cross-sectional view of the pump taken on or about line 7—7 of Figure 2.

Figure 8 is a view partly in elevation and partly in section of the heat retaining water container.

Figure 9 is a cross-sectional view through the same.

Figure 10 is an end elevation of the water container, showing the lever for operating the closure caps and for controlling the means for establishing a water connection between the pipe leading from the pump and the vertical inlet and discharge pipes within the water container.

Figure 11 is a plan view of the water container with parts in section.

Referring now to the letters of reference placed upon the drawings:

A, denotes a motor driven vehicle, B the usual internal combustion engine or prime mover, and C a radiator connected with the water cooling circulating system of the engine.

D, is a manifold connecting the water-jacket of the engine with the radiator.

10 E, denotes an engine starter of usual construction, E' is a gear on the starter shaft in mesh with a gear F on the shaft F'.

15 G is a gear keyed to the shaft F' adapted to slide upon the shaft that it may be brought into mesh with the gear H through the operation of the foot lever I.

J indicates a gear in mesh with the gear F, loosely mounted on the shaft J'.

20 K, denotes a clutch, actuated by the foot lever K' adapted to establish a driving connection between the gear J and the shaft J'.

25 L, indicates a worm gear on the shaft J' in mesh with a like gear L^a fitted with a crank arm L^b having a link connection L^c with the piston rod M of the pump N.

30 P, designates a plural valve chamber, having a connection P' with the bottom of the radiator C, and housing the usual drain-off or pet-cock P², below the radiator.

35 Q, indicates a water delivery pipe leading from the valve chamber P to the top of the radiator provided with a check-valve Q' to prevent the return of water through said pipe.

40 R, denotes a three-way valve located in the chamber P directly below the pipe Q, adapted to admit the delivery of water to the pipe Q when in the position shown in Figure 2, or the withdrawal of the water from the radiator when in the position shown in Figure 3.

45 S and T respectively denote two two-way valves housed in the valve chamber P;— and U and V are pipes connecting said valves with the pump N.

50 S' is a passage connecting the chamber S² in the valve chamber P with a passage T', in turn communicating with a pipe T² leading to the heat-retaining water chamber W;—preferably located beneath the driver's seat (see Figure 1).

55 The passage S' in the plural valve chamber is under the control of a check-valve S². S⁴ is a screw plug through which access may be had to the check-valve. In order to provide for the synchronous operation of the valves R, S, and T, they are respectively fitted with segmental intermeshing gears R^a, S^a, and T^a.

60 T^b denotes a rocker arm mounted on the trunnion of the valve T. T^c denotes a push-rod extending from the rocker arm to the instrument board T^d, in front of the driver's seat, where it is fitted with a knob for con-

venient operation of the valves by the driver of the vehicle.

Referring now to the heat-retaining water chamber W shown in Figures 1 and 2 of the drawings, W' W' W' designate a plural 70 number of water tanks in adjacent relation to each other and preferably located beneath the driver's seat. The tanks each consist of an inner chamber W^b spaced from the outer chamber, the construction being somewhat 75 similar in principle to the so-called "thermos" bottle.

W^c is an open ended tube extending from a neck W^d formed in the top of the outer tank to a point near the bottom of the inner tank. W^e is a float adapted to seat an air vent valve W^f in the upper wall of the tank chamber upon the tank being filled with water.

W^g is a rocking pipe journaled in an extension of the side walls of the tank. W^h is a gear mounted on an end of the pipe W^g, in mesh with an idle-gear Wⁱ which in turn meshes with a segmental gear W^k on the end of an operating lever W^l mounted on the 90 rod W^m which is also journaled in the upward extension of the tank walls. W^p, W^p, W^p, are closure caps supported on arms Wⁿ carried by the rod W^m adapted upon the operation of the lever W^l to simultaneously 95 close the necks W^d of the several tanks.

The rocking pipe W^g is closed at a point approximately midway of its length as shown in Figure 11, and is then provided with a projecting chamber or manifold X, 100 from which extends a series of pipes X', each pipe terminating in a nipple X², adapted to enter the open end of the respective tubes W^c, of the several tanks, upon the pipe W^g being rocked by the gears W^h and 105 Wⁱ,—in turn actuated by the lever W^l.

Referring again to the pump N:—when it is desired to withdraw the water from the radiator the starting motor E is first energized in the usual manner, the clutch K is 110 then operated by the foot lever K', to actuate the gears J and J', whereby the piston M', of the pump N is reciprocated.

The push-rod T² is then manually actuated to adjust the valves R, S, and T to the position occupied in Fig. 3, thereby permitting the water to be withdrawn from the radiator through the plural valve chamber P, thence by way of the passage r upwardly through the valve T, through the pipe V, through the 120 induction valve N^a, filling the pump cylinder as the piston moves to the left. Upon the return stroke of the piston the water in the pump cylinder is forced out through the eduction valve N^b, through the pipe U, into 125 the valve chamber P, through the valve S, passage-way S', raising the check-valve S³, into the passage T', and thence through the pipe T², to the pipe W^g, into the heat retaining water chamber W. The pipe W^g being 130

first manually rocked by the lever W^1 to connect the several nipples X^2 , with their respective vertical tubes W^c , thereby delivering the water into the several tanks. Simultaneously with the eduction of water from the right hand end of the cylinder, water is drawn into the cylinder from the radiator through the induction valve N^a , at the left hand end of the cylinder;—to be forced out through the eduction valve N^b , into the water heat-retaining water chamber W , upon the next stroke of the piston, in the manner just described;—the operation being repeated until all of the water contained in the radiator and cooling system has been delivered to the heat-retaining water chamber W .

If desired any condensation which may gather in the pipe P may be drained through the pet-cock P^2 or if it is desired to introduce fresh water into the cooling system, the water in the radiator may be withdrawn in the usual manner through the pet-cock P^2 .

Upon the delivery of the water into the cooling system from the heat-retaining water chamber, the pipe W^c is rocked by the lever W^1 , thereby withdrawing the nipples X^2 , from the open end of the pipes W^c , the closure caps W^p simultaneously closing the neck of the container through the rocking action of the rod W^m from which they are suspended.

When it is desired to return the water back to the radiator the closure caps are raised by the rocking lever W^1 , and a connection made between the nipples X^2 and the vertical pipes as before. The pump is then started as previously described; the reciprocation of its piston drawing the water from the chamber W through the pipe T^2 passage T' , the valve T , the pipe V , through the induction valve N^a , into the pump cylinder.

Upon the return stroke of the piston the water is forced out of the cylinder through the eduction valve N^b , passage U' , pipe U , valves S , and R , pipe Q , check-valve Q' , into the radiator C . It will now be apparent that after each stroke of the piston, the water previously delivered to the cylinder will be ejected from one end of the pump cylinder while water is drawn in at the opposite end of the cylinder, to be in turn ejected from the cylinder upon the return stroke of the piston, for delivery to the radiator, or vice versa.

If the car is not provided with a "starter" or in the event of the starter being out of order, the pump N , may be manually operated by the lever M^a .

Having thus described my invention what I claim is:

1. In a device of the character described, a radiator connected with the water cooling system of an internal combustion engine, a heat-retaining water container, a pump, pipe connections between the pump and radiator,

and between the pump and the heat-retaining water container, a valve chamber housing a plural number of valves, adapted to direct the water from the radiator to the pump and to the heat-retaining water chamber or in a converse direction, a train of gears adapted to operate said valves simultaneously, and means for operating said pump.

2. In a device of the character described, a radiator connected with the water cooling system of an internal combustion engine, a heat-retaining water container, a double acting pump, pipe connections between the pump and radiator and between the pump and the heat-retaining water container, a valve chamber housing a plural number of valves adapted to be simultaneously operated, said valves being adapted to direct the water from the radiator to the pump and thence to the heat-retaining water chamber or in a converse direction, and a rocking member carried by said water container adapted to establish a water connection between said pipe and said container or to disconnect same and simultaneously apply a closure to the opening into said container.

3. In a device of the character described, a heat-retaining water container, an open-ended pipe leading from the neck of said container to a point near the bottom of the container, a radiator, suitable piping leading from the radiator to the heat-retaining water container, a rocking pipe connected with said piping fitted with a goose neck adapted when tilted to establish a water connection with said open-ended pipe, means for manually rocking said pipe, and means for delivering water from the radiator to the heat-retaining water container, or conversely from the latter to the radiator.

4. In a device of the character described, a heat-retaining water container comprising a plurality of separate tanks, an open ended pipe leading downwardly from a neck of each tank, a radiator connected with the water cooling system of an internal combustion engine, a rocking pipe suitably journaled and provided with nipples respectively adapted to enter the upper end of said open ended pipes, a double-acting pump, piping leading from the radiator to the pump and from the pump to the rocking pipe, and a plurality of simultaneously operated valves under manual control for governing the direction of the water from the radiator to the pump and thence to the heat-retaining water container or conversely therefrom to the radiator as required.

5. In a device of the character described, a radiator connected with the water cooling system of an internal combustion engine, a heat-retaining water container having a double-wall spaced apart, a downwardly directed open pipe leading from the outer

wall to a point near the lower end of the inner chamber, a neck surrounding the upper end of said pipe, an air vent between the inner chamber and the neck, a float 5 valve adapted to close said vent, a rocking pipe suitably journaled in the wall of said container provided with nipples adapted to enter the open ends of said downwardly directed pipes, means for operating said 10 rocking pipe, a pipe connection between the radiator and the rocking pipe, means for delivering water from the radiator to said

water container or conversely from the latter to the radiator, means for controlling the direction taken by the water, and means for 15 simultaneously closing the necks of said water containers, synchronously with the removal of the nipples from said pipes.

In testimony whereof, I sign this specification in the presence of two witnesses.

THEODORE A. MILUTIN.
